UNITED STATES PATENT OFFICE

2,404,563

WRITING DEVICE

Martin Berliner, New York, N. Y., assignor to
 Bermat Products Corp., New York, N. Y., a corporation of New York

Application February 2, 1945, Serial No. 575,743

5 Claims. (Cl. 35—66)

1

This invention relates to writing devices for permanent use, and more particularly to a writing device susceptible of being operated to render indicia on its surface readily indiscernible or to efface such indicia.

A writing device of such type includes a writing unit consisting of a plurality of successive layers, outer layers and intermediate layers, respectively, the uppermost layer being transparent and being exposed to view at a window of the casing of the device.

In order to produce indicia on the writing device, pressure is exerted on the transparent uppermost layer against a thin, translucent sheet to be impressed upon layers therebelow, the latter including a preferably black, wax-covered support which coats with said translucent sheet or layer.

In order to efface the indicia which may be viewed through the transparent uppermost layer, a separation of the translucent sheet from the wax-covered support has to be effectuated.

In practice it has been found that such devices do not properly and adequately function under high humidity and when higher temperatures are prevailing. This deficiency becomes more apparent when the writing device is set in a wedge-shaped casing or housing to be used on a desk and where the additional problem arises of uniformly operating the device over its entire area down to its lowermost extremity.

The present invention does away with those and other disadvantages and drawbacks in the manipulation of such writing devices.

It is therefore one of the objects of the invention to provide means for obtaining a uniform and longer stroke for operating the implement used for separating the aforesaid layers and without enlarging or substantially modifying the casing as heretofore used.

It is another object of the invention to provide an efficient, relatively short and compact writing device of the aforesaid type, which is simplified with respect to its construction and manipulation and assures speedy and proper functioning during any atmospheric conditions.

It is a further object of the invention to provide locking means for maintaining the writing unit temporarily and firmly in operative position, said locking means including an indicator which discloses or makes the desired position of said locking means conspicuous from without the casing.

Still another object of the invention is to provide locking means affording when in inoperative position, clearance for effectuation of the stroke.

which is necessary to bring about full action of the implement for separation of the layers of the writing unit.

Yet, another object of this invention is to provide a gradual fixation of the locking device so that no part of the writing unit may be actuated and the latter is protected from displacement as long as the locking device is in operative position.

These and other objects and advantages of the invention will become more apparent as the following description of the embodiment of the invention progresses which are illustrated on the attached drawing, in which:

Fig. 1 is a top plan view of the writing device made in accordance with this invention.

Fig. 2 is a side-elevational view; and

Fig. 3 is a bottom plan view of the device shown in Fig. 1.

Fig. 4 shows the writing device as seen in Fig. 3 with removed bottom.

Fig. 5 shows a fragmentary view in perspective of one of the lower corners of the device as illustrated in Fig. 4.

Fig. 6 is a longitudinal, sectional view on an enlarged scale of the device, shown in Fig. 5.

Fig. 7 shows the device as seen in Fig. 6 in a different position.

Fig. 8 shows a rear-elevational view of the device illustrated in Fig. 1 but on an enlarged scale.

Figs. 9, 10 and 11 show fragmentary, sectional views of details located in the interior of the device of Fig. 1 to which reference is made in the specification.

Referring now in particular to the drawing, there is shown in Figs. 1 to 3 a casing 20 having the window 21 at which is exposed to view a writing unit 22. Figs. 1 and 2 further show the button 23 for actuating the writing unit in order to efface any indicia 24 visible through the uppermost layer of the writing unit at window 21.

The casing 20 is wedge-shaped (Fig. 2) and has the legs 25, 26, 27 and 28 forming depressions of the base plate 29 of the device. Fixed within the rear wall 30 of the device is a string 31 carrying a stylus 32 to impress indicia on writing unit 22. The front surface 33 of the writing device 20 has a groove 34 forming a rest for stylus or pencil 32 when not in use.

As clearly illustrated in Figs. 4 and 6, the hollow frame 35 houses the writing unit or pad 22 having the metal bottom plate 36 which includes a substantially rectangular, raised portion 37a offset with respect to its upper surface 37 for a purpose later described. Bottom plate

36 further carries on its upper end a lever 38 movable together with screw 39 which fixedly engages button or element 23. Lever 38 may be swung by turning button 23 to its locking position, as seen in Figs. 1 to 4, 6 and 8.

The writing unit 22 further comprises a transparent sheet 40, preferably made from acetate and underlying the window 21, and a tissue or translucent sheet 41 carried by a frame 42 having the window 43.

Frame 42 is firmly held in position within the hollow of frame 35 by means of holding pins or projections 44, 44a at the lower part (Figs. 4 and 5) of frame 35, and further by means of a rivet 45 passing through respective openings provided in upper frame part of frame 35, of sheet 40 and of frame 42 carrying tissue sheet 41. Against frame 42 carrying on its upper surface tissue sheet 41 releasably abuts the upper surface 37 of bottom plate 36 which firmly carries on its raised portion 37a a colored wax layer 47. Bottom plate 36 is held in position within frame 35 by means of the aforesaid projections 44, 44a stamped out of the forward rim 48 of frame 35. Bottom plate 36 underlies with the lowermost end of its underface 36a projections 44, 44a and is thus retained in engagement with frame 42. Frame 42 is arranged with respect to bottom plate 36 in superposed position. Bottom plate 36 is further held in position within frame 35 by said element or stud 23 guided in and extending through opening 23a provided in the upper portion of frame 35 of casing 20.

In order to assure releasable pressure of wax layer 47 carrying raised portion 37a against the underface of tissue sheet 41, a spring member 50 is provided which is secured on a rod 49 traversing frame 35 and held in position thereon in openings 51. These openings 51 are arranged in opposed side walls 52, 53 of frame 35 and at a location thereof which ensures a long stroke for the movement of stud 23, as will be later described.

As can be seen in Figs. 4, 6 and 7, spring 50 is provided with an upwardly projecting portion 50a abutting against the underface 36a of frame 35 and further with upwardly extending legs 50b abutting against the upper portion of underface 36a of bottom plate 36.

As can be easily realized, upon impressing transparent sheet 40 by means of stylus 32 against the tissue sheet 41 and the underlying wax layer 47 carried by raised portion 37 of bottom plate 36, indicia 24 thus produced will be made visible through the transparent sheet 40. By now pressing stud element 23 downwardly to perform a stroke from the position shown in Fig. 6 to a position shown in Fig. 7, the colored wax layer 47 carrying bottom plate 36 will be moved relatively to and spaced or separated from translucent tissue sheet 41 and transparent sheet 40, thereby causing effacement of the indicia 24 previously discernible through transparent sheet 40. During the aforesaid stroke, bottom plate 36 swings about the retainer pins 44, 44a to such an extent that even indicia appearing at the lowermost portion of sheet 40 and exposed to view in window 21 are made effectively indiscernible.

In order to bring about a free swinging movement about retainer pins 44, 44a, frame plate 42 as well as bottom plate 36 have lateral cut outs 54, 54a which extend from their outer ends toward said pins. Bottom plate 36 or frame plate 42 may be provided with lateral stopping means 55, 55a (Fig. 4) in order to prevent disengag-

ment of bottom plate 36 from projections 44, 44a within frame 35.

According to the present invention, rod 49 which carries the spring 50 is disposed adjacent the lowermost edge of the side walls 52, 53 and affords an increased stroke of the bottom plate 36 relatively to transparent sheet 40 and translucent sheet 41 whereby the particular advantage is obtained that button 23 may be pressed to such an extreme position that a full clearance between the upper waxed layer 47 and the translucent sheet 41 is achieved along the entire length of the latter.

This result is of importance for the effective functioning of the writing device even under high humidity and other unfavorable conditions depending upon the influence of the atmosphere.

The positioning of the rod 49 opposite button 23 further has the advantage of providing a stop or abutment for the end of button 23 which, as illustrated in Fig. 7, contacts in said extreme position said rod 49.

In order to impair the movement of button 23 in the event that no effacement of the indicia produced on the translucent sheet 41 is desired, interfitting formations forming locking means are provided according to the invention so as to releasably fix in position bottom plate 36 carrying the wax layer 47. To this end, button element 23 may be rotated to bring about movement of lever 38 from a position as indicated in dot-dash line at 38a to a position as illustrated in Fig. 8. By turning element 23 to the effect that lever 38 (being one of the interfitting formations) may be swung in the direction of arrow A to the position B (Fig. 4), the forward end 38b is caused to enter a slot 56 (being the other of the interfitting formations) which has an inclined portion 57 and a substantially horizontal portion 58. When the forward end 38b enters the inclined portion 57 and is then further moved to the horizontal portion 58 thereof, a gradual pressure of the bottom plate 36 against translucent sheet 41 is obtained, as may be easily visualized.

In the position as illustrated in Figs. 1 to 4, 6 and 8, the indicia producing writing unit or pad 22 is held with its parts 40, 41, 47 and 36 in firm and tight engagement with one another.

In such position, the impression of these parts of which the writing unit 22 consists is readily facilitated and contributes to a clear and unblurred appearance and discernibility of the indicia. When the writing device is held in locked position, effacement of the indicia cannot be had before the aforesaid fitting formations become disengaged, whereby the lever 38 will be moved out of its locking position in slot 56, in which the projecting lever end 38b is clearly visible from the outside (Fig. 1).

As can be seen in Figs. 6 and 7, base plate 29 frictionally engages the lower ends of rear wall 30, side walls 52, 53, and rim 48 and may rest against rod 49 in fixed position and thus assures a horizontal alignment and contact with the surface of a table on which the wedge-shaped casing 20 of the writing device may be placed.

As many possible embodiments of the above invention may be made, and as many changes might be made in the embodiment above set forth, it is to be understood that all matters hereinbefore disclosed or shown in the accompanying drawing are to be interpreted as illustrative and not in a limiting sense.

Having thus described the invention, what is

claimed as new and desired to be secured by Letters Patent is:

1. In a writing pad of the kind described contained within a casing and having a translucent sheet pressed upon and caused to adhere to a colored wax layer; a push button seated in said casing and operable from without said casing to space said translucent sheet from said wax layer, and engageable interfitting formations forming locking means, said interfitting formations being connected with said push button and being provided in said casing, respectively, whereby said push button is prevented from spacing said translucent sheet from said wax layer upon engagement of said interfitting formations of said locking means.

2. A writing device of the kind described having a casing enclosing a translucent sheet pressed upon and caused to adhere to a colored wax layer comprising an element projecting from within said casing therewithout and operable for moving said translucent sheet relatively to said wax layer for spacing the same from said translucent sheet, and locking means including engageable interfitting formations, said interfitting formations being respectively disposed on said casing and at said element, whereby upon movement of said element for engagement of said interfitting formations with each other operation of said element is impeded.

3. The combination, in a writing device of the kind described having a casing enclosing a translucent sheet pressed upon and caused to adhere to a colored wax layer, of a push button seated

in said casing and operable to move said translucent sheet relatively to said wax layer for spacing the same from one another, with locking means arranged for actuation by said push button, whereby in one position of said locking means the operation of said push button is impeded, while in another position of said locking means said push button is released for movement so as to space said wax layer from said translucent sheet.

4. The combination, in a writing device of the kind described having a casing enclosing a translucent sheet pressed upon and caused to adhere to a colored wax layer, of an element extending from said casing and operable to move said translucent sheet relatively to said wax layer for spacing the same from one another, with locking means arranged for actuation by said element, said locking means comprising a lever connected with said element, and a slot provided in said casing and engageable and disengageable by said lever, whereby upon engagement of said lever with said slot the operation of said element is impeded, while said lever when disengaging said slot releases said element for movement to space said wax layer from said translucent sheet.

5. The combination according to claim 4, characterized in that said slot has an inclined portion and a substantially horizontal portion, whereby upon engagement of said lever with said slot a gradual pressure of said wax layer against said translucent sheet is achieved.

MARTIN BERLINER.
